UNITED STATES PATENT OFFICE.

ELsie GREENHOW BANKS, OF TORONTO, ONTARIO, CANADA.

DESIGN FOR A PURSE.

43,334.

Specification for Design.

Patented Dec. 10, 1912.

Application filed July 3, 1912. Serial No. 707,635. Term of patent 3½ years.

To all whom it may concern:

Be it known that I, ELSIE GREENHOW BANKS, a subject of the King of Great Britain, residing at the city of Toronto, in the county of York, Province of Ontario, Canada, have invented a new, original, and ornamental Design for Purses, of which the following is a specification.

Referring to the accompanying drawing, the figure is a perspective view of the purse showing my new design.

I claim—

The ornamental design for a purse as shown.

In testimony whereof I have signed my name to this specification in the presence of the two subscribing witnesses.

ELsie GREENHOW BANKS.

Witnesses:

A. CAMPBELL,
W. G. McMILLAN.
